UNITED STATES PATENT OFFICE

ERNEST L. MCFARLAND, OF STRASBURG, VIRGINIA

COMBINATION TABLE

Application filed July 31, 1931. Serial No. 554,313.

The present invention relates generally to furniture and more particularly to a new and useful improvement in tables and has for its primary object to provide, in a manner as hereinafter set forth, a device of this character embodying a novel construction, combination and arrangement of parts whereby the same may be expeditiously converted from a conventional table such as a card table, to a sewing table including a needlework bag.

Another important object of the invention is to provide a combination table of the aforementioned character which is foldable, thereby permitting the same to be stored in a small space when desired.

Other objects of the invention are to provide a combination table of the character described which may be expeditiously set up for use or taken down, which will be simple in construction, strong, durable, light in weight, attractive in appearance, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation showing the table set up for use as a card table.

Figure 2 is a view showing the top removed and with the legs folded with a needle work bag suspended thereon.

Figure 3 is a detail view in elevation of the needle work bag.

Figure 4 is a view in side elevation showing the device set up for use as a sewing table.

Figure 5 is a view in top plan of the device ready for use as a sewing table.

Figure 6 is a view in bottom plan of the table top.

Figure 7 is a view in vertical longitudinal section through the table showing all of the elements thereof in the position in which the same are disposed for use.

Figure 8 is a fragmentary detail view in vertical longitudinal section through one end portion of the table top showing the same inverted and showing the compartment therein.

Referring now to the drawings in detail, it will be seen that the table constituting the present invention comprises pairs of crossed legs 1 and 2 which are pivotally connected together in their ends, as at 3. Suitable braces 4 extend between the pairs of legs 1 and 2. Extending between the upper end portions of the pairs of legs are the rods 5 which are preferably of wood.

The reference numeral 6 designates a top having a suitable cover 7 thereon and extending around the marginal portions of said top 6 on the lower side thereof is a substantially rectangular frame including the end members 8 and the side members 9. The marginal portions of the cover 7 are downturned and secured between the strips 10 and the members 8 and 9, said strips being secured by suitable means to said members 8 and 9.

Secured to the lower side of the top 6 and extending between the end members 8 are the spaced, parallel, longitudinal bars 11 having secured to their lower sides the longitudinally spaced, oppositely disposed hooks or abutments 12 for engagement with the rods 5 for limiting the swinging movement of the pairs of legs 1 and 2 in one direction and for mounting the table top in position on the legs. This is illustrated to advantage in Figure 7 of the drawings.

Transverse bars 13 extend between the longitudinal bars 11 in spaced relation to the end members 8 and hingedly mounted, as at 14, on said transverse bars 13 are the doors 15 which are secured in closed position by suitable keepers 16 on the end members 8. It will thus be seen that the elements 6, 8 and 11 define compartments 17 for the reception of any desired articles 18 to which access may be had through the medium of the doors 15.

Hingedly mounted for swinging movement to the upper portions of the pair of legs 1 is a leaf 19 having a hook or abutment

20 secured to its lower side for operative engagement by a brace 21 having its end portions journaled in the legs 1. As will be obvious, the brace 21 is adapted to support the 5 leaf 19 in a horizontal position. A keeper 22 is mounted on one of the legs 1 for engagement with the leaf 19 for retaining said leaf between the pair of legs 1 when said leaf is not in use.

10 The reference numeral 23 designates a fabric needle work bag having its upper portions gathered and provided with a hem 24 through which is inserted an elastic 25, portions of said elastic 25 extending outwardly 15 from the hem and having thereon rings 26 for engagement with the hooks 27 which are provided on the upper end portions of the legs 1 and 2 for supporting the needle work bag 23 in position thereon.

20 In use, when the device is to be used as a card table, the leaf 19 is dropped to its inoperative position between the upper portions of the legs 1 and the top 6 is mounted in position on the legs 1 and 2 by spreading 25 said legs and engaging the rods 5 in the hooks or abutments 12. If desired, the needlework bag 23 may be left in position between the upper portions of the legs 1 and 2 and beneath the top 6 or said needlework bag may 30 be removed. The compartments 17 provide convenient storage space for card game accessories, such as pencils, score cards, decks or the like. When removing the articles 35 from the compartments 17 or placing said articles therein, it may be found convenient to invert the table top as suggested in Figure 8 of the drawings but this may not be necessary.

When the table is to be used for sewing, 40 the top 6 is removed and the leaf 19 is swung upwardly to its operative position and supported by the brace 21. The needlework bag 23 is also mounted in position. When the table is not in use and is stored away the 45 leaf 19 is disposed in its inoperative position and retained by the keeper 22 and, of course, the top 6 is removed. If desired, the needle work bag 23 may be left in engagement with the legs 1 and 2 and said legs are folded, as 50 suggested in Figure 2 of the drawings. It will thus be seen that the table may be conveniently stored in a small space.

It is believed that the many advantages of a combination table in accordance with this 55 invention will be readily understood, and although the preferred embodiment of the invention is as illustrated and described, it is to be understood that changes in the details of construction and in the combination and 60 arrangement of parts may be resorted to which will fall within the scope of the invention as claimed.

What is claimed is:—

1. A table comprising pairs of pivotally connected, crossed supporting legs, rods ex-

tending between the upper ends of each pair of legs, a top, a frame secured to the marginal portions of the lower side of the top and including end members and side members, spaced, parallel bars secured to the lower side 70 of the top and extending between the end members of the frame, oppositely disposed hooks secured to the longitudinal bars and engageable with the rods for limiting the swinging movement of the legs in one direction relative to each other and for removably mounting the top in position on said legs. 75

2. A table comprising pairs of pivotally connected, crossed supporting legs, rods extending between the upper ends of each pair of legs, a top, a frame secured to the marginal portions of the lower side of the top and including end members and side members, spaced, parallel bars secured to the lower side of the top and extending between the end members of the frame, oppositely disposed hooks secured to the longitudinal bars and engageable with the rods for limiting the swinging movement of the legs in one direction relative to each other and for removably mounting the top in position on said legs, transverse bars extending between the longitudinal bars in spaced parallelism with the end members of the frame and, in conjunction with said end members and with the top and the longitudinal bars, providing compartments, doors hingedly mounted on the transverse bars, and keepers mounted on the end members of the frame and engageable with the doors for retaining said doors in closed 100 position, said doors providing means of access through the compartments.

In testimony whereof I affix my signature.

ERNEST L. McFARLAND.
